ELECTROMAGNETIC RECORDING ARRANGE-
MENT

Semi Begun, Berlin, Germany, assignor to C.
Lorenz Aktiengesellschaft, Berlin-Tempelhof,
Germany, a company

Application March 19, 1935, Serial No. 11,887
In Germany March 16, 1934

2 Claims. (Cl. 177—311)

Electromagnetic recording machines on the Poulsen principle are frequently arranged to be governed by a suitable controlling mechanism from a distantly located place, especially if they are to record dictations or telephonic communications.

In this case it is desirable that the speaking person may be able to ascertain how long the machine will still be able to record; that is, to ascertain the length of that piece of steel wire or tape which is still available for recording.

It has been proposed to connect with an indicating device fitted to the frame or casing in which the spools carrying this wire or tape are mounted, means which after the movement of the wire has been finished will stop the machine and transmit a signal to the controlling station, i. e. the place where the speaking person is. Such a provision, however, does not enable him to finish his dictation in due time or to shorten it.

In accordance with the invention, signals are transmitted to the speaking person each time the record carrier, for instance the said wire or tape, has been moved a predetermined distance, so that the speaking person shall at any time be able to ascertain how much time is still available for transmitting a dictation or a telephonic communication or, in other words, how much of the record carrier has already been used or is still available.

One embodiment of the invention is described hereafter by way of example, reference being had to the accompanying drawing which is a partially diagrammatic and partially sectioned elevation thereof.

Mounted in a frame piece 1' are two spools 1, 2 which are provided with the record carrier, i. e. a steel wire or tape, for example, in such a manner that this wire or the like can be wound from one spool onto the other and then be recoiled, as is customary with telephones and like devices. The record carrier is not shown. Spool 1 is adapted to be driven by a motor 3. The frame piece 1' has a bearing 4 for a screw 5. The screw 5 is by a suitable gearing 6 connected with the motor 3 and carries a nut 7 arranged to be displaced along the screw. Projecting into the path of this nut are studs 8 which are seated on contact springs 9 and are guided in a bar 10. This and the studs 8 consist of an electrically insulating material. To each spring 9 a lamp 11 is allotted. A ringer 12 is adapted to be governed by each of the springs 9. These signalling means 11, 12 and a battery 13 are disposed at the place 14 where the speaking person is.

The motor 3 rotates the spool 1 so as to wind the wire or the like, not shown, from spool 2 onto spool 1, and through the gearing 6 acts at the same time to revolve the screw 5. The nut 7 consequently moves along the screw in the direction of the arrow and depresses the studs 8 one after the other. The studs 8 in their turn depress the springs 9 and are restored by these to their normal position as soon as the nut leaves them. In the drawing, one stud 8 and spring 9 are shown as depressed. The lamps 11 are hereby successively cut in and out. Each time the ringer 12 is likewise included in the circuit.

The nut 7 by its position on the screw 5 indicates how far the record carrier has been wound on the spool 1 or unwound from spool 2. The indicators 11, 12 enable a similar supervision to be made at place 14 although this is remote from the recording machine.

In order to effect a saving in wires the time during which each spring 9 is depressed so as to close a circuit may be different from the time during which any of the other springs is depressed. In order to perform this studs 8 may be provided with heads 15 which differ from each other in width. By this means special acoustic or optic signals may be produced at place 14 through the medium of special arrangements of relays or by similar contrivances.

In the example shown the lamp 11 represented at Z is lit longer than the lamp 11 at Y and this lit longer than the lamp 11 at X while the ringer 12 is actuated accordingly long each time, so that the signals at 14 will be the more impressive the nearer the end of the period of time available for recording.

What is claimed is:

1. In an electric recording arrangement, the combination of a recording machine and a remotely located dictating station, a plurality of indicators at said station, means cooperating with said machine for movement in accordance with the progressive recording action of said machine, a plurality of electric contacts controlled by said cooperating means connected for actuating said indicators, and means for causing said contacts to be progressively actuated for periods of successively greater duration, whereby said indicated signals are progressively more impressive.

2. In an electromagnetic recording arrangement, the combination of a recording machine with a remote dictating station therefor, a signal indicator at this station, progressive means mov-

able in response to the recording actuation of said machine, a plurality of signal contacts, a plurality of contact changing members provided with cam surfaces arranged to be successively moved by said progressive means to successively close said signal contacts, the cam surfaces of

said members being of progressively different length, and means connecting said contacts to said signal indicator whereby the indicated signals are of different length to indicate the progress of said recording machine.
